UNITED STATES PATENT OFFICE.

ANDREW POOL AND RALPH KAAN, OF INDIANA HARBOR, INDIANA.

SMOKE AND DUST CONSUMER.

1,171,750.

Specification of Letters Patent.

Patented Feb. 15, 1916.

Application filed October 21, 1915. Serial No. 57,072.

To all whom it may concern:

Be it known that we, ANDREW POOL and RALPH KAAN, citizens of the United States, residing at Indiana Harbor, in the county of 5 Lake and State of Indiana, have invented certain new and useful Improvements in Smoke and Dust Consumers; and we do declare the following to be a full, clear, and 10 exact description of the invention, such as will enable others skilled in the art to which it appertains to make and use the same.

This invention relates to improvements in smoke and dust consumers which may be applied either to locomotive smoke stacks or 15 those used on stationary furnaces and boilers.

One object of the invention is to provide a hood for the smoke stack having suitably arranged therein a water spray pipe, the 20 smoke being caused to pass through the spray on its way from the smoke stack to the outer air.

A further object is to provide a dust catcher in which the solid particles contained 25 in the smoke are precipitated by the water from the spray pipe.

A still further object is to provide a combined scraper and conveyer within this dust catcher for carrying the dust to a suitable 30 opening in the bottom of the catcher from which a discharge pipe leads.

With the above objects in view, our invention resides in the novel features of construction which will be hereinafter more 35 particularly described and claimed and shown in the drawings wherein:

Figure 1 represents a side elevation of the upper portion of a smoke stack showing our improved consumer applied thereto; Fig. 2 40 is a central vertical longitudinal section taken on the line 2—2 of Fig. 1, and Figs. 3 and 4 are respectively transverse sections taken on the lines 3—3 and 4—4 of Fig. 2.

In the drawings, our invention is shown 45 applied to the usual smoke stack 1 by means of brackets 2.

The invention comprises a hood 3 having a top 4 and side walls 5 which depend slightly below the top of the smoke stack as 50 shown in Fig. 2. This hood is substantially cylindrical, the top 4 thereof being flat and having depending from its inner face an inverted conical-shaped deflector 6 substantially the diameter of the smoke stack, the 55 apex of said deflector extending downwardly to about the top of the stack 1 as shown.

An additional deflector 7 is mounted within the hood 3 by the brackets 2, said deflector being substantially cylindrical in shape with open ends. This deflector 7 is spaced from 60 and parallel to the wall 5 of the hood, and spaced from the stack 1; the upper edge of the deflector 7 is also spaced from the top 4 of the hood, while its lower edge is in the plane of the top of the smoke stack. From 65 the foregoing, it will be seen that the smoke passing from the stack is deflected by the conical-shaped deflector 6 toward the wall 5 of the hood, but the deflector 7 guides the same upwardly toward the top 4, from 70 which it passes downwardly between the wall 5 and the outer side of the deflector 7, and from this passage way between the wall of the hood and the deflector 7 the light particles of smoke pass upwardly around 75 the lower edge of the wall 5 and escape. The passage of the smoke from the stack 1 to the hood is indicated by the arrows.

In order to precipitate the heavy particles of dust from the volume of smoke which 80 issues from the stack, we provide a substantially circular spray pipe 8 which preferably lies on the upper edge of the deflector 7, water being fed to this spray pipe from the supply pipe 9 which leads up the side 85 of the stack from any suitable source of supply. The holes in this pipe 8 extend transversely therethrough in a horizontal plane, thus causing the water to spray outwardly at right angles to the direction of the course 90 of the smoke. Thus the smoke is forced to pass through the water twice on its way from the stack to the outer atmosphere. The precipitated particles of dust and cinders are caught in a dust pan 10 which 95 surrounds the stack 1 at a considerable distance below the lower edge of the hood. This pan 10 has a bottom 11 having an opening 12 therein to allow the accumulated dust and water to pass through a discharge 100 pipe 13 which leads down the side of the stack 1 to a suitable receptacle. The top edge of the outer side of the pan forms a seat for a ring 14 having gear teeth 15 on its outer edge which are adapted to intermesh with the teeth of a spur gear 16. The gear 16 is mounted on a suitable shaft 17 driven by any preferred means. The inner side of the ring 14 which projects within the pan 10 is provided with a plurality of 110 scrapers 18 which extend inwardly from said ring to the inner side of the pan.

These scrapers collect the dust and water which drops from the hood 3 and convey them to the opening 12 in the bottom of the pan, it being obvious that the ring 14 upon 5 which the scrapers are mounted is caused to rotate by rotation of the spur gear 16.

While we have shown the hood 3 and the deflector 7 as mounted on the upper end of the stack 1, by the suitably arranged brackets 10 2, it is obvious that separate brackets may be provided for mounting each of them separately, or that the deflector 7 could be fixed within the hood 3 by any preferred means.

15 While describing the elements best adapted for performing the operation of the smoke consumer, it is obvious that various changes in the general arrangement of this hood and its pan may be resorted to without departing from the spirit or sacrificing any of the principles of this invention.

We claim as our invention:

1. The combination with a smoke stack; 25 of a hood over said stack and spaced therefrom, said hood being closed at its top and open at its bottom, the lower edge of the wall thereof being extended below the top of said stack, a substantially cylindrical open-ended deflector within said hood and spaced from the top and side walls thereof, 30 whereby smoke from the stack is deflected upwardly and then downwardly and out the open bottom of said hood, a water spray pipe on the upper edge of said deflector to spray the water both inwardly and outwardly in a substantially horizontal plane, thereby causing the smoke to pass twice 35 through the water during its passage from the stack to the outer atmosphere.

40 2. The combination with a smoke stack; of a hood disposed thereabove, said hood

being closed at its top and open at its bottom, whereby the smoke is deflected downwardly, a water spray pipe therein, a dust pan disposed around said stack below said 45 open-bottomed hood and having an opening in its bottom, said pan being substantially U-shaped in cross section with a flat bottom, a plurality of scrapers in said pan to convey the dust deposited therein to the 50 discharge opening, the straight edges of said scrapers being movable over the flat bottom of said pan, a ring seated on one of the upper edges of said pan and carrying the scrapers, said scrapers being substantially the width of the pan to maintain the ring in operative position, and means for revolving said ring to move the scrapers. 55

3. The combination with a smoke stack; of a hood over said stack and spaced therefrom, the lower edge of the wall of said hood being extended below the top of the stack, a substantially cylindrical open ended deflector within said hood and spaced from the top and side walls thereof, a water spray 60 pipe on the upper edge of said deflector, an additional inverted cone-shaped deflector depending from the top of said hood within the first mentioned deflector, a dust pan disposed around said stack and having an opening in its bottom, a discharge pipe leading therefrom, a plurality of rotatably mounted scrapers in said pan, and means for moving said scrapers. 65

In testimony whereof we have hereunto 70 set our hands in presence of two subscribing witnesses.

ANDREW POOL
RALPH KAAN.
